UNITED STATES PATENT OFFICE

1,922,715

MANUFACTURE OF ARTIFICIAL FILAMENTS,
THREADS, AND THE LIKE

Reginald Henry John Riley, Spondon, near Derby, England, assignor to Celanese Corporation of America, a Corporation of Delaware

Application August 26, 1930, Serial No. 477,838,
and in Great Britain June 5, 1930

3 Claims. (Cl. 18—8)

This invention relates to apparatus for the manufacture of artificial silk and other artificial filaments, threads, ribbons, straw, or the like, (hereafter referred to as "filaments"), and is especially applicable to apparatus for the manufacture of such materials by the dry or evaporative method of spinning.

The object of the invention is to enable two jets or nozzles to be used in series on a single pipe or member for supplying spinning solution to the jets or nozzles.

British patent application No. 27,042/29 filed 5th September 1929, or the corresponding U. S. application S. No. 476,304 filed August 19, 1930 describes in detail two forms of means for removably connecting one jet or nozzle in series with another, the two forms comprising respectively an attachment adapted to be clamped on to the means for securing one jet or nozzle to its supply pipe or member, and an attachment adapted to be screwed on to said securing means.

The present invention comprises a further form of means by which one jet or nozzle can be secured to or removed from the supply pipe or member for the spinning solution without interfering with the attachment of the jet or nozzle to which the solution is fed directly from the supply pipe or member.

The jet or nozzle (hereafter referred to as the "first jet") to which spinning solution is fed directly by the supply pipe or member may be formed integrally with or detachably or otherwise attached to the supply pipe or member. Conveniently it takes the form of a perforated metal disc or cup which may be attached by a union or like engaging with the supply pipe or member or with a member attached thereto, or it may be soldered or brazed thereto.

The jet or nozzle (hereafter referred to as the "second jet") in series with the first jet may be of any convenient form, as for instance a perforated metal disc or cup, and is secured to the supply pipe or member by an attachment which is slid over the first jet and locked in position by spring-pressed balls or plungers or by set screws which engage the supply pipe or member or a member fitted thereto or a union or the like by which the first jet is attached to the supply pipe or member. These means enable the second jet to be very quickly removed and replaced without interfering with the first jet.

The means for attaching the second jet to the supply pipe or member may be so arranged as to permit of the attachment without requiring any modification of the means usually employed for

securing the first jet to the supply pipe or member; or the supply pipe or member, or the means for securing the first jet thereto, may be modified to receive the means for attaching the second jet. The second jet is preferably arranged to fit closely to the first jet, and the filtering of the spinning solution is preferably effected before the solution arrives at the first jet.

The mounting of a second jet in series with the first in such a manner that it can be removed and replaced without interfering with the first jet enables the second jet to be removed without loss of pressure, wastage of spinning solution, or other inconveniences usually attendant upon removing the spinning jet. The first jet serves as a pressure retaining member after removal of the second jet and is formed with one or more holes of sufficient total area to enable the second jet to receive an adequate supply of spinning solution. The total area of said hole or holes is preferably such that the pressure in the supply pipe or member remains approximately the same after removal of the second jet as when it is in use. For example, the first jet may be provided with a single hole of slightly greater area than the total area of the orifice or orifices of the second jet. The first jet may, however, serve as an additional filtering means for the spinning solution, in which case it may be provided with a number of holes not substantially greater than, and preferably considerably smaller than, the orifices in the second jet.

The apparatus may, moreover, be employed as a simple means for changing the character of the product spun, either as regards the number of filaments extruded or their denier, or both, by allowing the first jet to be used as a spinning jet through which one or more relatively large filaments or a plurality of fine or very fine filaments are extruded, and then attaching a second jet to serve as a spinning jet for the extrusion of one or more relatively large filaments or a plurality of fine or very fine filaments of different denier and/or number from those extruded through the first jet. Thus, the first jet may be arranged to spin a thread consisting of a number of fine or very fine filaments and by attaching a second jet, having a suitable number of spinning orifices which may be round, slit-shaped or otherwise formed, the output may be changed to relatively few filaments of fairly high denier, or even to a single high denier filament.

One form of jet fitting and attachment according to the invention is illustrated in the accompanying drawing, but it is to be under-

stood that this, together with the following description, is given by way of example only, and is in no way limitative.

Fig. 1 is a plan view, partly in section, of the 5 jet fitting which is shown, also partly in section, on the right-hand side of Fig. 2, the left-hand side of Fig. 2 showing a slight modification of the fitting.

The first jet 15 is attached to the supply pipe 10 11 by means of nuts 12, 14. The second jet 26 is secured in a cylinder 35 adapted to slide over the nut 14. The jet 26 is held against the under side of an inwardly projecting ring 36 inside the cylinder 35, by means of a locking ring 37, in 15 which is cut a slot 39 to receive a key for the purpose of securing the jet in the cylinder. The upper surface of the ring 36 fits against the lower surface of the nut 14. The cylinder 35 is locked in place over the nut 14 by means of 20 spring-pressed balls 41, the springs 42 and the balls 41 being contained in cups 43, screwed into the side of the cylinder 35. The balls 41 fit over the top edge of the nut 14 to hold the cylinder in place. Alternative means for securing the 25 cylinder in place is shown on the left-hand side of Fig. 2. Set screws 44 are screwed into the body of the cylinder and are coned at their ends so as to fit over the top edge of the nut 14. The screws 44 or the cups 43 are knurled, or may 30 be formed with a slot or recess to receive a screw driver or key for the purpose of adjustment or removal. This form of attachment may be used without modification of the means for securing the jet 15 to the pipe 11. Packing rings 16, 40 35 are used to make tight joints between the jets 15, 26 and the body of the jet fitting or attachment.

The jet 15 is shown as having a number of orifices 29, and the jet 26 only a single orifice 33, the jet 15 thus serving as a pressure retaining member or filter. It will be understood, however, that the output of the jet, either as regards number or size of the filaments spun, can be readily varied, either by using jets 15 and 26 having a different number and size of orifices and allowing the jet 15 to serve as the spinning jet while the jet 26 is absent, or by using the jet 15 as a pressure retaining member to reduce wastage during the changing of one jet 26 for another having a different number and size of orifices.

What I claim and desire to secure by Letters Patent is:—

1. A device for use in the manufacture of artificial filaments comprising, in combination with an existing jet and a supporting member for carrying said jet, an auxiliary jet and means for attaching said auxiliary jet to the existing jet, said means including a socket-like member adapted to support said auxiliary jet and shaped in conformity with said supporting member so as to be slidably engageable therewith, and locking means carried by the socket-like member for holding the said members, when interengaged, against disengagement.

2. A device according to claim 1, comprising spring-pressed sliding abutment locking means for holding the said members against disengagement.

3. A device according to claim 1, comprising screw-in plunger locking means for holding the said members against disengagement.

REGINALD HENRY JOHN RILEY.
